Primary Examiner — Nathan M Johnston(74) *Attorney, Agent, or Firm* — Tuggle Duggins P.A.;
Blake P. Hurt(57) **CLAIM**

The ornamental design for a syringe adapter, as shown and described.

DESCRIPTION

FIG. 1 is a top, front, right side perspective view of a syringe adapter showing my new design;

FIG. 2 is a bottom, rear, left side perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof, the rear elevational view being a mirror image thereof; and,

FIG. 8 is a cross-sectional view as taken along lines 3-3 of FIG. 3.

1 Claim, 7 Drawing Sheets(56)
